UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

DRIVING MECHANISM FOR WEB FEEDING AND CUTTING MACHINES.

Application filed November 9, 1923. Serial No. 673,772.

The object of my invention is to provide a connection between the feeding and driving mechanisms, which connection may be easily and accurately adjusted to compensate for longer or shorter sheets, without disconnecting the parts.

My invention comprises a longitudinally adjustable web feeding and cutting mechanism, a driving mechanism and a connecting shaft having upper and lower gears meshing at all times with their respective gears of the web feeding and cutting mechanism and the driving mechanism, the shaft having a sliding interlocked connection with its gear which meshes with the driving mechanism, whereby the shaft may be swung into different angular positions without disconnecting the parts as the web feeding and cutting mechanism is adjusted to cut sheets of different lengths from the traveling web; means being provided for securing the shaft in its adjusted positions.

A practical embodiment of my invention is represented in the accompanying drawings, in which

Fig. 1 represents in side elevation those portions of a web feeding and cutting machine which include my invention, the parts being shown adjusted for cutting sheets of a predetermined length.

Fig. 2 represents a similar view with the parts shown adjusted for cutting sheets of a different length.

Fig. 3 represents a detail face view of the carriage frame at the point where the upper shaft hanger is adjustably secured thereto.

Fig. 4 represents a detail face view of the main frame at the point where the lower shaft hanger is adjustably secured thereto.

Fig. 5 represents a detail section on an enlarged scale, taken in the plane of the line V—V of Fig. 1.

Fig. 6 represents a detail section taken in the plane of the line VI—VI of Fig. 5.

The main frame of the machine which carries the driving mechanism, is denoted by 1 and the frame which carries the web feeding and cutting mechanism, is denoted by 2. This carriage frame is adjustable longitudinally along the main frame to provide for the cutting of sheets of varying lengths.

The connecting shaft 3 is provided with upper and lower gears 4 and 5, the upper gear 4 meshing at all times with a gear 6

of the web feeding and cutting mechanism, mounted on the cutter shaft 8, and the lower gear 5 meshing at all times with a gear 7 of the driving mechanism, mounted loosely on the stud shaft 9.

The gear 6 is shown as rotatively adjustable with respect to its shaft 8 by providing a flanged sleeve 10, keyed to the shaft 8, the face of the flange having a concentric undercut groove 11 for receiving the heads of an annular series of bolts 12, the shanks of which pass through the web of the gear 6. Nuts 13 engage said shanks to clamp the gear 6 to the said flanged sleeve 10.

The upper shaft hanger 14 engages the face of the carriage frame 2 and is pivoted on the shaft 8. This hanger is provided with oppositely disposed wings 15, 16 having elongated slots 17, 18 concentric with the axis of the gear 6, through which slots 75 fastening bolts 19, 20 pass, each into engagement with one of a series of holes 21, 22 in the carriage frame 2, for securing the hanger to the carriage in any of its adjusted positions.

The lower shaft hanger 23 engages the face of a bracket 24 of the main frame 1 and it is pivoted on the stud shaft 9. This hanger is provided with wings 25, 26, in the face of which there is located an undercut groove 27 concentric with the axis of the gear 7 for receiving the head of a fastening bolt 28, the shank of which passes through a hole in the main frame 1. A nut engages said shank for securing the hanger to the frame.

A gear 30 of the driving mechanism is rotatively mounted on the stud shaft 9 and the driving mechanism gear 7 is shown as adjustably secured to the gear 30 by providing the gear 30 with an annular series of bolts 31, the shanks of which enter an annular series of holes in the web of the gear 7. The axis of the connecting shaft 3 passes through the axis of the gear 7. This is provided for in the present instance by an eye 32 in the stud shaft 9, through which the connecting shaft 3 extends.

The arrangement of the parts as herein shown and described will permit the longitudinal adjustment of the web feeding and cutting carriage within wide limits, to provide for the cutting of sheets of varying lengths, without disconnecting the web feeding and cutting mechanism from its driving

mechanism. After the web feeding and cutting carriage has been adjusted longitudinally to the desired position for cutting sheets of a predetermined length, the upper and lower shaft hangers may be secured to their respective frames, thus forming a rigid connection between the driving mechanism and the web feeding and cutting mechanism.

The bolts 31, carried by the gear 30, have their shanks weakened at 33 where they enter the web of the gear 7 so that the bolts will shear off and prevent the breakage of the gears when an abnormal strain is brought on them by the choking of the free operation of the cutters in trying to cut through several thicknesses of burlap or other material at the same time.

The driving relationship between the driving mechanism and the web feeding and cutting mechanism is obtained by loosening the nuts 13 on the bolts 12, thus permitting the gear 6 to be rotated with respect to the flanged sleeve 10 which is keyed to the shaft 8. After the gear 6 has been rotatively adjusted to the desired position, the gear may be secured to the flanged sleeve 10 in this adjustment by tightening the nuts 13.

The provision of the series of holes 21 and 22 in the carriage frame enables the bolts 19 and 20 to be changed from one hole to another, to permit a very wide range of movement of the carriage along the main frame.

It will thus be seen that I have provided for a wide range of adjustments by a very simple combination of parts which are readily accessible and quickly brought into the desired relationship.

It is evident that various changes may be resorted to in the construction, form and arrangement of the several parts without departing from the spirit and scope of my invention; and hence, I do not intend to be limited to the particular embodiment herein shown and described, but—

What I claim is:—

1. A main frame, a carriage adjustable longitudinally along the same, a gear carried by the carriage, a driving mechanism carried by the main frame, a gear on said driving mechanism and a connecting shaft having upper and lower gears meshing respectively with said gears, said connecting shaft having a sliding interlocked connec-

tion with one of its gears to permit the shaft to be moved to different angular positions by the adjustment of said carriage, without disconnecting the parts, and means for securing the shaft in its different angular positions comprising upper and lower shaft hangers having elongated slots and fastening bolts slideable in their respective slots and engaging the carriage and main frame respectively.

2. A main frame, a carriage adjustable longitudinally along the same, a gear carried by the carriage, a driving mechanism carried by the main frame, a gear on said driving mechanism and a connecting shaft having upper and lower gears meshing respectively with said gears, said connecting shaft having a sliding interlocked connection with one of its gears to permit the shaft to be moved to different angular positions by the adjustment of said carriage, without disconnecting the parts, and means for securing the shaft in its different angular positions comprising upper and lower shaft hangers having elongated slots and fastening bolts slideable in their respective slots and engaging the carriage and main frame respectively, the fastening bolts for the upper shaft hanger being adjustably positioned on the carriage.

3. A main frame, a carriage adjustable longitudinally along the same, a gear carried by the carriage, a driving mechanism carried by the main frame, a gear on said driving mechanism and a connecting shaft having upper and lower gears meshing respectively with said gears, said connecting shaft having a sliding interlocked connection with its lower gear to permit the shaft to be moved to different angular positions by the adjustment of said carriage, without disconnecting the parts, and means for securing the shaft in its different angular positions comprising upper and lower shaft hangers having elongated slots and fastening bolts slideable in their respective slots and engaging the carriage and main frame respectively, the fastening bolts for the upper shaft hanger being adjustably positioned on the carriage.

In testimony, that I claim the foregoing as my invention, I have signed my name this 7th day of November, 1923.

HOWARD M. BARBER.
